Inventor

John Schatt

United States Patent Office.

JOHN SCHATT, OF PHILADELPHIA, PENNSYLVANIA, ASSIGNOR TO HIMSELF
AND SAMUEL P. MERVINE, JR., OF SAME PLACE.

Letters Patent No. 66,256, dated July 2, 1867.

IMPROVEMENT IN DRY GAS-METERS.

The Schedule referred to in these Letters Patent and making part of the same.

TO ALL WHOM IT MAY CONCERN:

Be it known that I, JOHN SCHATT, of the city of Philadelphia, in the State of Pennsylvania, have invented a new and useful Improvement in the Dry Gas-Meter; and I do hereby declare that the following is a full, clear, and exact description of the construction and operation of the same, reference being had to the accompanying drawings, and to the letters of reference marked thereon.

My invention relates to the manner of connecting the "leather" to the "rings" of the disks and the diaphragm, which together with the said leather form the measuring-chamber of a dry gas-meter, and consists in attaching the edges of the said leather to the rings respectively by applying and securing a single cord in combination with the side edge of the leather within a groove, subsequently closed around the edge of the ring, substantially as hereinafter described. Referring to the drawings—

Figure 1 is a vertical diametrical section, and

Figure 2 a transverse section of the rings and the connecting leather of a measuring-chamber.

Figure 3 being an enlarged section of part of the same.

Like letters of reference indicating the same parts when in the different figures.

A A' are the two "rings" of a chamber, B the connecting "leather," and C the cord; the disks and diaphragm to which the rings are to be soldered, not being necessary to explain the invention, are not shown in the drawing. The rings A each consists of a narrow strip of sheet metal connected together at its ends so as to form a band. One edge a'' is then turned outward so as to form a narrow flange or face for soldering the ring to either the usual disk or diaphragm, as the case may be. Along near the opposite edge of the said ring I then indent a semicircular groove a''', and taking a piece of twine or other cord suitable for the purpose, I confine thereby the edge side of the usual leather B firmly down in the said groove a''', securing the two ends of the said cord C together by a hitch or tie, and adjust the wrinkles of the confined edge side of the leather uniformly around the ring, so as to remove any laps in the leather under the cord, (see the left-hand side of fig. 1.) I now close the groove a''' over the cord and surrounding leather by running it between the rolling-dies of the well-known closing machine used by tin-workers, and thus produce a perfectly gas-tight connection between the edge of the leather B and the ring A, as represented at a'''' in figs. 1, 2, and 3.

Heretofore in the manufacture of dry gas-meters requiring this form of chamber, the leather has been secured to the rings by winding a cord several times tightly around the flat surface of the latter with the side edge of the leather between, but such mode is not only difficult of execution, but the tension of the cord varies during the service of the meter from hydrometric causes, and consequently the chambers leak or cease to be gas-tight, and are therefore not reliable as measurers of the gas passing through the meter; whereas in my described mode of securing the leather to the rings it will be readily seen that as the cord C and the portion of the leather B around it are enclosed tightly and closely within the metallic case or bead a'''', moisture cannot reach the interior of the latter, and therefore the juncture will remain perfectly gas-tight and reliable.

Having thus fully described my improvement in the manufacture of dry gas-meters, what I claim as my invention, and desire to secure by Letters Patent, is confined to the following, viz:

I claim the attaching leather B and the ring A together by means of the single cord C and the groove a''', closed tightly over the said cord and leather, substantially in the manner described and for the purpose specified.

JOHN SCHATT.
